UNITED STATES PATENT OFFICE.

GUY RANDALL VAIL, OF BATTLE CREEK, MICHIGAN.

COMBINED VACUUM-PRODUCING AND BOILER-FEEDING APPARATUS.

1,332,698.

Specification of Letters Patent.

Patented Mar. 2, 1920.

Application filed June 12, 1919. Serial No. 303,701.

To all whom it may concern:

Be it known that I, GUY R. VAIL, a citizen of the United States, residing at Battle Creek, in the county of Calhoun and State of Michigan, have invented certain new and useful Improvements in Combined Vacuum-Producing and Boiler-Feeding Apparatus; and I hereby declare that the following is a full, clear, and exact description thereof, reference being had to the accompanying drawings, which form part of this specification.

This invention relates to low pressure steam heating systems in which steam is fed from a boiler or generator to a heating system, and circulation of steam under low pressure is maintained in the system by producing a partial vacuum at the outlet end thereof; by which means the steam is circulated through the system and the water of condensation withdrawn therefrom, and surplus water of condensation is returned to the boiler.

The apparatus in brief comprises a double suction pump casing of the centrifugal type, having two separated inlet or suction openings and an intermediate discharge chamber; one of the inlet openings being connected by a pipe to a tank which is vented to the atmosphere, the other inlet of the pump is connected to the outlet end of the heating system; the discharge chamber of the pump is connected to the tank by means of a pipe having a valve. A float inside of the tank controls the opening and closing of the said valve according to variations of the water level in the tank. Another check-valved pipe connects the discharge chamber of the pump to the boiler. Within the pump casing is a centrifugal pump impeller having two suction openings on its opposite sides or ends and a common discharge opening at its periphery. One side of the impeller acts to draw water from the open tank; the other side acts to draw air and vapor and water from the return of the heating system.

In order to enable others to readily understand, adapt and use the invention I will explain one practical embodiment thereof, illustrated in the accompanying drawings, and the operation of such apparatus, (it be-

ing understood that the invention is not restricted to the specific construction of parts illustrated in the drawings) and will, 55 then set forth in the claims the novel essentials of the invention and the novel combinations of elements and novel constructions of parts for all of which protection is desired.

In said drawings:

Figure 1 is a top plan view of the complete apparatus.

Fig. 2 is an end elevation of the apparatus shown in Fig. 1.

Fig. 3 is an enlarged partial side elevation thereof, the pump being shown in longitudinal vertical section.

Figs. 4 and 5 are enlarged sectional views of the pump-impeller.

As illustrated in the drawings I preferably employ a novel double suction centrifugal pump whose casing 1 has axially aligned inlet or suction openings 1^a, 1^b between which is a centrally disposed circumferential discharge chamber 1^c, having an outlet 1^d.

Mounted axially of and centrally within the casing 1 is a double rotary impeller 2 (see Figs. 4 and 5) the opposite sides of which impeller are similar so that it is adapted, when rotated, to create suction in both inlet openings, 1^a, 1^b of the casing, and to discharge into the chamber 1^c, creating a pressure therein.

As shown in Figs. 4 and 5 in each side of the impeller is a series of convolutely curved channels 2^a of different lengths arranged in similar groups, the channels in each group varying in length but all extending from the periphery of the impeller toward the center thereof; and the groups of channels are similar on opposite sides of the vertical center line of the impeller, so that the suction will be practically alike on both sides. The channels in opposite sides of the impeller converge toward the periphery of the impeller and merge, adjacent the periphery thereof, in common channels 2^b which discharge into the chamber 1^c. The operating portions of the impeller are thus practically alike, on each end or face thereof, and the impeller is adapted to create a suction on both sides or

ends and withdraw matter at its ends from the inlets 1^a, 1^b and discharge same at its periphery into the chamber 1^c.

The impeller is mounted upon a shaft 3 which extends axially through the casing 1 and the inlets 1^a, 1^b and chamber 1^c, so as to properly position the impeller in the casing.

The casing of the impeller may be of any suitable kind so constructed and proportioned that the impeller will run properly and create suction at both sides or ends and preferably discharge into a peripherally disposed chamber.

15 As shown the shaft 3 is provided with suitable stuffing boxes 3^a at the outer sides of the casing and exterior to the openings 1^a, 1^b, and the shaft bearings may be cooled and sealed by means of water introduced through 20 pipes 3^b connected by a short pipe 3^c with the outlet chamber 1^c of the pump as shown in Fig. 3.

The shaft 3 and impeller thereon may be rotated by any suitable means. Preferably 25 I employ an electric motor M of any suitable construction connected to the end of the shaft 3 as indicated in the drawings; this motor being mounted upon the base 9 which supports the other parts of the apparatus.

30 The inlet 1^a of the pump is connected by a pipe 4^a with the lower part of a water tank 4, of any suitable construction, preferably mounted upon the base 9, which tank may be provided with a water gage 4^b to show the 35 water level therein. This tank is also connected by a pipe 4^b to a pipe 1^c which is connected with the outlet 1^a of the chamber 1^c. Thus provision is made for a continuous or endless circuit of water from the tank 40 through the pipe 4^a port 1^a to the left hand side of the impeller to and through chamber 1^c and pipes 1^c and 4^b back into the tank.

The flow of water through this circuit may be controlled by a valve 4^c of any suitable 45 construction placed in pipe 4^b; and this valve may be automatically regulated by the water in tank 4 by suitable float-controlled means of any suitable construction.

As shown in Fig. 3 a float 5 in the tank 50 has its stem 5^a connected to a rock shaft 5^b one end of which projects out of the tank through a suitably packed opening and carries an arm 5^c which is connected by a link 5^d to a valve-operating lever 5^e, which is operatively engaged with the stem of the valve 4^c in any suitable manner, so that when the water in the tank is at the normal level the valve 4^c will remain open, but when the water rises above a certain level in the tank 60 the float will cause the valve 4^c to close; and thus the valve 4^c will be more or less closed or opened by the action of the float, according to the level of the water in the tank.

The pipe 1^c is connected by a pipe 1^f with 65 the boiler (not shown) at a point interme-

diate the valve 4^c and the pump. A check valve 1^g is placed in the pipe 1^f to prevent back flow of water from the boiler to the pump chamber 1^c or into the pipe 4^b.

The inlet port 1^b of the pump is connected 70 by suitable piping (not shown) to the return pipe or header of the heating system (not shown).

It will be obvious that when the pump is working the impeller will create a circulation of water from the tank to and through the left hand side of the impeller into chamber 1^c; and thence under ordinary conditions back through pipe 4^b to the tank. At the same time the right hand side of the 80 impeller will tend to create a vacuum in the heating system through the inlet 1^b; the aforesaid water circulation insuring the creation of a partial vacuum on the right hand side of the impeller. The apparatus 85 will thus tend to create a vacuum on the heating system and to return the water of condensation to the tank 4.

Preferably I provide the right hand side of the impeller with small perforations 2^a 90 connecting with the inner ends of passages 2^a so as to admit water from the water filled chamber in the casing surrounding the impeller into the passages 2^a at the air and steam suction side of the impeller. These 95 apertures will permit pressure of fluid in the casing to enter the channels 2^a at the right hand side of the impeller and insure the creation of suction in the heating system.

With this apparatus the impeller is always 100 water sealed, and when it is started it operates to circulate water in a closed circuit from the tank to and through the left hand side of the impeller back to the tank, and simultaneously to create a suction on the 105 right hand side of the impeller and in the heating system.

The water in the tank 4 should initially be at such a level as to insure the opening of the valve 4^c. The water from the tank 110 primes the impeller, and water drawn from the tank is returned thereto in a continuous circuit. The water passing through the left hand channels 2^a into and through the peripheral passages 2^b of the impeller serves to 115 produce suction in the right hand channels 2^a of the impeller which are also connected with the centrally disposed discharge passages 2^b, thus creating a partial vacuum in the heating system and the discharge of 120 vapors or water of condensation from the heating system into the chamber 1^c of the pump and thence into the tank.

As the water of condensation passes over 125 into the tank the water gradually accumulates in the tank and thus raises the float therein, and this causes the gradual closing of the valve 4^c, which in turn causes the pressure to rise in the discharge chamber 1^c of the pump. The impeller should be so pro- 130

- portioned and so driven as to enable it, if necessary, to accumulate sufficient pressure in the chamber 1° to force the excess water of condensation back into the boiler when 5 the water in the tank rises above the desired level, and the valve 4° is closed by action of the float, or closed to such an extent that all the water of condensation cannot pass back into the tank.
- 10 The impeller is preferably continuously driven, so that the action of the apparatus is automatic; and air, water and vapors are withdrawn from the heating system and discharged into the tank, which is always open, 15 so that there is no pressure therein, and any surplus water of condensation is returned to the boiler.

What I claim is:

1. In apparatus of the character specified, 20 a tank; a double suction pump having two suction inlets and a single discharge one of the suction inlets being connected with the return of a heating system; a pipe connecting the other suction inlet of the pump with the tank; and a pipe connecting the discharge of the pump with the tank and means for controlling the return of water from the pump to the tank.
2. In a combined vacuum producing and 30 boiler feeding apparatus; a tank; a double suction pump having two suction inlets and a single discharge, one of said suction inlets being connected with the return of a heating system; a pipe connecting the other suction inlet of the pump with the tank; a pipe connecting the discharge of the pump with the tank; and a valve in said pipe controlled by a float in the tank for regulating the return of water from the pump to the tank.
3. In a combined vacuum producing and 35 boiler feeding apparatus, a tank; a double suction pump having opposite suction inlets and an intermediate discharge chamber, and a double rotary impeller intermediate the suction inlets adapted to draw from both the suction inlets and discharge peripherally into the discharge chamber, one of the suction inlets being connected with the return of a heating system; a pipe connecting the other suction inlet of the pump with the tank; a pipe connecting the discharge of the pump with the tank; and means for controlling the return of water from the pump to the tank.
4. In an apparatus of the character specified, a tank; a double suction pump having opposite suction inlets and an intermediate discharge chamber, and a double rotary impeller intermediate the suction inlets adapted to draw fluid from the suction inlets and discharge the same peripherally into the discharge chamber, one of the suction inlets being connected with the return of a heating system; a pipe connecting the other suction inlet of the pump with the tank; a pipe

connecting the discharge of the pump with the tank; and a valve in said pipe controlled by a float in the tank for regulating the return of water from the pump to the tank.

5. In apparatus of the character specified, 70 a tank; a double suction pump having two suction inlets, and a single discharge, one of the suction inlets being connected with the return of a heating system; a pipe connecting the other suction inlet of the pump with the tank; and a pipe connecting the discharge of the pump with the tank and means for controlling the return of water from the pump to the tank; with means for connecting the discharge of the pump with a boiler, and means for preventing back flow of water from the boiler to the pump.

6. In a combined vacuum producing and 75 boiler feeding apparatus; a tank; a double suction pump having two suction inlets, and a single discharge, one of the suction inlets being connected with the return of a heating system; a pipe connecting the other suction inlet of the pump with the tank; a pipe connecting the discharge of the pump with the tank; and a valve in said pipe controlled by a float in the tank for regulating the return of water from the pump to the tank; with means for connecting the discharge of the pump with the boiler at a point intermediate 80 the valve and the pump, and a check valve in said means for preventing back flow of water from the boiler.

7. In a combined vacuum producing and 85 boiler feeding apparatus, a tank; a double suction pump having opposite suction inlets and an intermediate discharge chamber, and a double rotary impeller intermediate the suction inlets adapted to draw from both the suction inlets and discharge peripherally into 90 the discharge chamber, one of the suction inlets being connected with the return of a heating system; a pipe connecting the other suction inlet of the pump with the tank; a pipe connecting the discharge of the pump with the tank; and means for controlling the return of water from the pump to the tank; with means for connecting the discharge of the pump with a boiler, and a check valve in 95 said means for preventing back flow of water from the pump.

8. In an apparatus of the character specified, 100 a tank; a double suction pump having opposite suction inlets and an intermediate discharge chamber, and a double rotary impeller intermediate the suction inlets adapted to draw fluid from the suction inlets and discharge the same peripherally into the discharge chamber, one of the suction inlets being connected with the return of a heating 105 system; a pipe connecting the other suction inlet of the pump with the tank; a pipe connecting the discharge of the pump with the tank; and a valve in said pipe controlled by a float in the tank for regulating the return 110

120

125

130

of water from the pump to the tank; with a pipe connecting the discharge of the pump with a boiler, and a check valve for preventing back flow of water from the boiler to the

5 pump.

9. In apparatus of the character specified a rotary pump impeller having suction openings at opposite sides of its center, peripheral discharge outlets, and curved passages at opposite sides of its center leading from the suction openings to the peripheral discharge outlet, said impeller having apertures in one side wall for permitting fluid from the exterior of the impeller to enter the sides of the 10 adjacent passages, substantially as described.

10. In apparatus of the character specified a rotary pump impeller having suction openings at opposite sides of its center, peripheral discharge outlets, and curved passages at opposite sides of its center leading from the suction openings to the peripheral discharge 15 openings, said discharge passages being convolutely disposed and arranged in groups of varying length; said impeller having ap-

tures in one side wall near the inlet ends of the passages for permitting fluid from the exterior of the impeller to enter the sides of adjacent passages.

11. In an apparatus of the character specified a rotary pump casing having opposite axially disposed inlet openings, and an intermediate circumferentially disposed discharge chamber; with a rotary impeller mounted in the casing between and disposed axially of the inlet openings and having suction openings at opposite sides of its center, peripheral discharge outlets, and curved passages at opposite sides of its center leading from the suction openings to the peripheral discharge openings; said impeller having 20 apertures in one side near the inlet ends of the passages for permitting fluid from the exterior of the impeller to enter the adjacent 25 passages.

In testimony that I claim the foregoing as 30 my own, I affix my signature.

GUY RANDALL VAIL.
